FLOODLIGHT OR SIMILAR ARTICLE

William H. Morgan, Jr., 326 North St.,
Georgetown, Mass.

Filed Mar. 19, 1965, Ser. No. 84,457

Term of patent 14 years

(Cl. D48—20)

FIG. 1

FIG. 2

FIG. 3

FIG. 4

FIG. 5

FIGURE 1 is a side perspective view of a floodlight or similar article showing my new design with the support thereof shown fragmentarily for ease of illustration.

FIGURE 2 is an elevational view of the front of the floodlight or similar article shown in FIGURE 1.

FIGURE 3 is an elevational view of the rear of the floodlight or similar article shown in FIGURE 1.

FIGURE 4 is a side elevational view of the floodlight or similar article shown in FIGURE 1.

FIGURE 5 is a view of the top surface of the floodlight or similar article shown in FIGURE 1.

The support shown fragmentarily in FIGURES 1, 2, 4 and 5 is included for illustrative purposes only.

I claim:

The ornamental design for a floodlight or similar article, as shown and described.
